UNITED STATES PATENT OFFICE.

ALBERT J. BUHTZ, OF SEATTLE, WASHINGTON.

KNOCKDOWN BARREL.

1,116,793.

Specification of Letters Patent. Patented Nov. 10, 1914.

Application filed November 13, 1913. Serial No. 800,887.

To all whom it may concern:

Be it known that I, ALBERT J. BUHTZ, a citizen of the United States, and resident of Seattle, King county, Washington, have invented certain new and useful Improvements 5 in Knockdown Barrels, of which the following is a specification.

My invention relates to barrels and particularly to knock down barrels, or barrels 10 so constructed that they may be disassembled for shipping when empty.

The object of my invention is to produce an improved and more practical type of construction, whereby the barrels may be partially assembled into segments which will nest 15 for compactness of transportation and may be easily and cheaply assembled when they are to be used.

My invention comprises the novel parts 20 and combinations of parts which will be described in the specification and defined in the claims.

In the accompanying drawings I have 25 shown my invention in the form which is now preferred by me.

Figure 1 is an end view of a barrel constructed in accordance with my invention, the construction being that used where the head is to be removable and the head being 30 removed. Fig. 2 is an elevation and partial section of a barrel end. Fig. 3 shows in perspective one of the segmental binding strips used for the staves at the end where the head is to be removable. Fig. 4 is a perspective 35 view of a segmental binding strip as made for the end of the barrel where it is not required to remove the head. Fig. 5 shows, in perspective and nested as they would be for shipment, the three stave segments which 40 may be used to form the body of the barrel shown in Figs. 1 and 2. Fig. 6 shows the removable head. Fig. 7 is a section of a corner of a barrel showing how the head is secured in place and the corrugations by 45 which the bindings are more securely held in the staves. Fig. 8 is a cross section of a stave binding before it is put in place.

In my invention I assemble a number of staves so as to form a segment of the completed barrel. The size of these segments, that is, the number which would be required to make a barrel, may be somewhat varied, but I consider the most practical number to be three, and have shown a barrel having the 50 staves previously assembled into three like

segments. The staves are supposed to be of wood and, in general, of a standard type of construction. The staves 1 as I have herein shown them, do not have chamfered chines, nor are they crozed to receive the head. 60

A number of staves 1, sufficient to form a segment of the desired width, are secured together by sheet metal bindings 2 and 3, placed at opposite ends, these being longitudinally curved to conform to the curvature of the barrel. The binding pieces 2 and 3 are alike, except that the pieces 2 are modified in one way to permit ready insertion and removal of the head 4 after the barrel has been completely assembled. Each piece 70 2 and 3, is bent over the ends of the staves, so as to incase their ends. A section 20 extends from the outer end corner of the staves toward the center; the section 21 extends over the ends of the staves and the section 22 75 extends along the inner surface of the staves to a point substantially coincident with the outer surface of the head, where an inwardly projecting flange 23 is formed by bending the metal upon itself. The metal then continues toward the center of the barrel as a section 24 of a width substantially equal to the thickness of the head 4 and is then bent inwardly to form a flange 26 which engages 80 the inner surface of the head. 85

The above constructions are found alike in the binding strips used for both ends of the barrel, but the one which is placed at the end of the barrel which receives the removable head, is modified by having substantially one-half of the length of the flange 23 cut away. The portion cut away may be concentrated in one cut, as I have shown in the drawings, or it may be divided into separated parts. The head 4, which is placed in this end of the barrel, has its edge notched, or recessed to conform to the sections of the flange 23 which remains. That is, the gaps 41 match the sections of the flange which remain and the projecting parts 40 100 match with the gaps in the flange. In inserting the head the projections 40 are passed through the gaps in the flange 23 so as to rest upon the flange 26, and is then turned so as to bring it under the flange 23. 105 The other head is inserted at the time of assembling the barrel.

In assembling a segment, the ends of the staves are inserted within their binding pieces, the latter having been previously 110

shaped to the required form. At this time the cross section would be as shown in Fig. 8. To securely bind the whole together, certain parts of the binding piece preferably those which lie in the plane of the head, are crimped or corrugated, as shown at 25, the corrugations being pressed into the wood. These corrugations should preferably be offset from the normal plane of the plate, wholly at that side which is next the staves, as is shown in Fig. 7. These corrugations would thus be embedded in the staves and would then appear as shown in Fig. 7. The barrel segments thus formed may be nested, as shown in Fig. 5, for convenient shipping, the heads and hoops being also bundled. When the barrel is to be assembled, the segments which form the complete barrel are brought together and the bottom head inserted between the flanges 23 and 25 and hoops placed upon the barrel and driven tight. In Figs. 2 and 7 I have shown wire hoops 5, although any kind of hoops may be used.

25 By reason of the fact that the bindings employed to secure together the staves of a segment are made of sheet metal which hugs closely to the surface of the staves and by reason of their location at the ends of the staves, or at the chines, where the barrel is of the least diameter, they do not interfere with the application or removal of hoops of any of the kinds most commonly used. By reason of the fact that they embrace or are folded about the chines and further because of the inwardly projecting, head - holding flanges, they have a sufficient transverse depth in the direction of the diameter of the completed barrel, to give them such stiffness as will cause them to hold their shape under any ordinary handling conditions.

What I claim as my invention and desire to patent is:

1. In a barrel, in combination, staves, means permanently joining the ends of a plurality of staves to form separable and distinct segments, said means being provided with head securing members, and means for

securing said segments together to form a barrel body. 50

2. In a barrel, in combination, staves, metal bindings each inclosing and fixedly joining the ends of a plurality of staves to form separable and distinct segments, said binding members having inwardly projecting spaced flanges adapted to receive the head between them, and means for securing a plurality of segments together to form a barrel body. 55

3. In a barrel, in combination, staves, metal bindings embracing and fixedly secured upon the ends of a plurality of staves to form separable and distinct segments, said bindings at one end of the barrel having two inwardly projecting flanges separated lengthwise the barrel to receive the barrel head therebetween, and means independent of the said bindings for securing a plurality of the segments together to form a barrel body. 60 70

4. As an article of manufacture, a barrel segment composed of a plurality of bilged staves having metal bindings fixedly secured over their chines, said bindings being provided with head holding means and having transverse stiffness which maintains the curvature of the segment in conformity with that of the completed barrel. 75

5. In a barrel, in combination, staves, a sheet metal binding embracing the ends of a plurality of staves to form a segment, said binding being folded to, form two inwardly projecting flanges adapted to receive the head between them, the part of the metal connecting said flanges and the corresponding part of the outside arm of the binding having inwardly extending projections embedded in the staves, and hoops securing a plurality of segments to form the barrel. 80 85

In testimony whereof I have hereunto affixed my signature this 7th day of November, 1913.

ALBERT J. BUHTZ.
